US00D818751S

(12) **United States Design Patent** (10) **Patent No.:** **US D818,751 S**
(45) **Date of Patent:** **** May 29, 2018**

(54) **TABLE BASE**

(71) Applicant: **Liberty Procurement Co. Inc.**, Union, NJ (US)

(72) Inventor: **John Merritt**, Brooklyn, NY (US)

(73) Assignee: **Liberty Procurement Co., Inc.**, Union, NJ (US)

(**) Term: **15 Years**

(21) Appl. No.: **29/582,752**

(22) Filed: **Oct. 31, 2016**

Related U.S. Application Data

(62) Division of application No. 29/527,682, filed on May 21, 2015, now Pat. No. Des. 783,329.

(57) **CLAIM**

The ornamental design for a table base, as shown and described.

DESCRIPTION

FIG. 1 is a perspective view of a table base according to my new design;

FIG. 2 is a right-side elevation view thereof;

FIG. 3 is a left-side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines shown in the drawings represent portions of the table base that form no part of the claimed design.

1 Claim, 6 Drawing Sheets
